UNITED STATES PATENT OFFICE

PERRY H. HAMILTON, OF BALTIMORE, MARYLAND, ASSIGNOR TO MAINTENANCE EQUIPMENT COMPANY, OF CHICAGO, ILLINOIS, A CORPORATION OF ILLINOIS

WHEEL FLANGE OILER

Application filed July 13, 1928. Serial No. 292,401.

This invention relates to a wheel flange oiler, and more particularly to a device for projecting oil from a reservoir mounted adjacent the rail onto the flange of a car wheel and the side of the rail head. The present invention relates to certain improvements on the device disclosed and claimed in my co-pending application, Serial No. 262,452, filed March 17, 1928.

10 A receptacle or reservoir, holding a quantity of oil, is mounted adjacent that side of the rail at which the wheel flange travels. A pump mechanism mounted in the reservoir comprises a plunger positioned to be depressed by the wheel flange, thereby projecting oil through a discharge passage leading to a point adjacent the rail head from which the oil is thrown onto the wheel flange. Means is provided for elevating the plunger 15 after the wheel flange has passed by, whereby a new quantity of oil flows or is drawn from the reservoir into the pump cylinder.

In order to operate most efficiently, it is desirable that the plunger have a uniform stroke, that is each downward or oil-expelling stroke should be of substantially the same length. However, the car wheel flanges which engage the plunger to depress same vary considerably in diameter, and unless 25 some means is provided to compensate for this variation in the diameter of the flanges, the downward working strokes of the plunger will vary accordingly.

The particular object of the invention is 30 to provide means for securing uniform working strokes of the plunger in both directions, regardless of the variations in the diameter of the car wheel flanges. This object is attained by providing stops for limiting the 35 stroke of the plunger in each direction and making a portion of the plunger compressible. The plunger is so positioned that it will be forced downward for its complete stroke by wheel flanges of the smallest diameter, and the compressible portion of the 40 plunger will permit flanges of larger diameter to pass over the plunger without increasing the stroke.

Other objects and advantages of this invention will be more apparent from the fol-

lowing detailed description of one approved form of the apparatus.

In the accompanying drawings:

Fig. 1 is a plan view of the apparatus mounted on the rail. 55

Fig. 2 is a longitudinal vertical section, taken substantially on the line 2—2 of Fig. 1.

Fig. 3 is a transverse vertical section on a larger scale, taken substantially on the line 3—3 of Fig. 1. 60

Fig. 4 is a horizontal section, taken substantially on the line 4—4 of Fig. 3.

The improved wheel flange oiler comprises an elongated receptacle closed at its bottom 1, its rear wall 2, front wall 3, and end walls 4. The rear wall 2 is adapted to be secured to a supporting plate 5 by any suitable means, such as bolts 6. The supporting plate 5 is shaped at its top and bottom edges to fit between the head 7 and base flange 8 at one 70 side of the rail, and the ends 9 of the plate extend beyond the ends of the receptacle so that the assembly may conveniently be secured to the web 10 of the rail by means of screw bolts 11 passed through the web, or 75 any equivalent attaching means. The receptacle serves as a reservoir to house the oil supply.

Mounted against the bottom 1 and rear wall 2 of the receptacle is a block 12 having 80 a vertical rear flange or plate 13 by which the block may be mounted against the rear wall 2 by means of screws 14. A pump cylinder 15 is formed vertically within the block 12, this cylinder being closed at its 85 lower end and open at its upper end. An oil discharge passage 16 in the block is conveniently formed by making a vertically extending groove or slot in the rear wall 13 of the block, the open side of this groove 90 being closed by the rear wall 2 of the receptacle when the parts are assembled. The lower end of discharge passage 16 is connected with the lower portion of cylinder 15 by a laterally extending passage 17 in which 95 is housed a ball valve 18, normally held against the converging inlet end of passage 17 by the spring 19. This one-way valve serves to permit oil to be discharged from cylinder 15 into the passage 16 but prevents 100

oil from being drawn back from passage 16 into the cylinder.

A pair of horizontally positioned arcuate ports 20 are formed in the side walls of the cylinder block at an intermediate height. These ports are of small vertical height, but have as great an arcuate length as the structure will permit to provide for the free passage of oil from the reservoir into the cylinder. A bushing 21 is fitted securely within the cylinder 15, the bushing being formed with arcuate ports 22 aligned with the ports 20 but narrower vertically than the ports 20. It is more convenient to cast the ports 20 of greater size than is desired, and to machine the narrower ports 22 within the bushing 21 before the bushing is fitted within the cylinder 15.

A plunger or piston 23 is fitted within the bushing 21 to operate vertically, the plunger having a limited travel past the ports 22 in both directions. The upper end of plunger 23 is formed with an upwardly projecting collar 24, of greater diameter than the plunger 23 so as to form a lower shoulder 25. A head 26 comprises an upper cap member 27, adapted to be engaged and depressed by the car wheel flange indicated in dotted lines at 28, and a lower member 29 threaded into cap 27 at 30. The member 29 is formed with a lower inwardly extending flange 31 adapted to engage beneath the shoulder 25 on plunger 23, and with an upper outwardly extending flange 32 adapted to engage beneath the cover plate 33 on the reservoir to limit the upward movement of the head and plunger. A rather strong compression spring 34 is housed within the head 26 and interposed between the head and top of plunger 23 so as to normally hold the head up with flange 31 in engagement with shoulder 25, in which position the head and plunger will normally operate vertically as a unit. A second compression spring 35, is confined between flange 32 of the head and a shoulder 36 on cylinder block 12, so as to normally elevate the plunger until its upward movement is stopped by the engagement of flange 32 with the cover plate 33. A stud 37 projecting upwardly from the base of cylinder 15 serves as a stop to limit the downward movement of plunger 23.

Cover plate 33 is formed with an opening 38 for receiving the head 26, and an annular packing ring 39 mounted in a groove in plate 33 serves to seal the opening 30 and prevent the entrance of foreign substances without materially interfering with the vertical movement of the plunger. The cover plate 33 is removably secured in any suitable manner to the upper face of the receptacle, for example by means of the screws 40. A suitable filling opening for replenishing the oil supply may be provided in plate 33, this

opening being here shown as closed by a screw plug 41.

An arcuate hood 42 projects outwardly from the upper portion of cylinder block 12, above the ports 22, and terminates at its lower end adjacent the bottom wall 1 of the receptacle so as to leave an open oil passage 43 between the lower edge of the hood and the bottom of the reservoir. Passage 43 should be of sufficient height to permit the free and unimpeded flow of oil from the reservoir into the suction chamber 44 formed beneath hood 42.

In operation, the reservoir will be filled with oil to some convenient height, as indicated at α in Fig. 3, and the cylinder 15 beneath plunger 23 and also the discharge passage 16 will be filled with oil. As a wheel passes over this apparatus, the wheel flange 28 will depress the head 26 forcing down the plunger against the resistance of the spring 35. The spring 34 is stronger than the oil pressure that will be developed within the pump cylinder, so that this spring will not be compressed until the downward movement of plunger 23 has been stopped by engagement with the stud 37. The apparatus is so designed that wheel flanges 28 of the least diameter will depress plunger 23 sufficiently to cause a complete stroke thereof, bringing the plunger into engagement with stop 37. When wheel flanges of greater diameter pass over the apparatus, the complete stroke will be imparted to plunger 23, and the spring 34 will then be compressed to permit the larger flange 28 to pass thereover, the head 26 sliding down over the plunger 23. After the wheel has passed by, the springs 34 and 35 will both expand so as to move the head 26 back to its extreme upper limit of movement on plunger 23, and to move the assembled head and plunger upwardly until this movement is limited by engagement with cover plate 33.

As the plunger is forced downwardly, after the lower end of the plunger has closed the ports 22 further downward movement of the plunger will force oil from cylinder 15 past the one-way ball valve 18 into discharge passage 16, the oil being projected upwardly from this passage against the wheel flange 28 at the side of the rail head 7. After the wheel has passed, the spring 35 will elevate the plunger thereby creating a suction in cylinder 15 which will immediately close the ball valve 18 so as to prevent the oil which remains in discharge passage 16 from being drawn back into the cylinder. As the lower end of plunger 23 uncovers the ports 22 and passes thereabove, the suction created in cylinder 15 will draw oil into the cylinder from the suction chamber 44 beneath the hood 42. If a sufficient head of oil were maintained within the cylinder, this hood 34 would be unnecessary, but when the oil level

- in the reservoir is not much higher than the ports 22, the suction would break through the top of the oil supply thus sucking air into the cylinder so that the pump would lose its prime and become inoperative. The oil used in these devices is rather thick and sluggish, thereby increasing the danger of sucking through the upper surface of the oil supply. The hood 42 serves to form a suction chamber 44 around the ports 22 which will be maintained full of oil by a siphon action so that the oil level in the reservoir may become quite low (as indicated at y) and the mechanism will still remain operative.
- It will be apparent that this device will apply oil to only a relatively small portion of the car wheel flange, but this oil is distributed for a greater distance on the wheel flange by the rotating wheel and by wiping against the side of rail head 7. By using several of these oiling devices in series, spaced at suitable intervals along the rail, the entire circumference of the car wheel flange may be quickly oiled. Ordinarily two or more of these pumping devices will be mounted within the same receptacle or reservoir, but for convenience of illustration I have shown but one of them.
- I claim:
1. In a wheel flange oiler comprising a reservoir for holding oil adapted to be positioned adjacent the rail, a pump including a cylinder and a plunger in the cylinder positioned to be depressed by the car wheel flange, a port connecting the cylinder with the reservoir, and a passage for discharging oil from the pump against the flange, a stop for limiting the downward stroke of the plunger, a head telescopically fitted to the plunger to be engaged by the flange, means for elevating the plunger, and a compressible spring positioned between the head and plunger, said spring being of sufficient strength to successfully resist movement of the head with relation to the plunger until the downward stroke of the plunger has been completed by engagement with the stop.
  2. In a wheel flange oiler comprising a reservoir for holding oil adapted to be positioned adjacent the rail, a pump including a cylinder and a plunger in the cylinder positioned to be depressed by the car wheel flange, a port connecting the cylinder with the reservoir, and a passage for discharging oil from the pump against the flange, a stop for limiting the downward stroke of the plunger, a spring positioned to elevate the plunger, a head telescopically fitted to the plunger to be engaged by the flange, and a second spring positioned between the head and plunger, said second spring being of sufficient strength to prevent relative movement between the head and plunger until the plunger has engaged the stop.
  3. In a wheel flange oiler comprising a reservoir for holding oil adapted to be positioned adjacent the rail, a cylinder block positioned in the reservoir, a plunger in the cylinder, a port in the cylinder wall for receiving oil from the reservoir, said port being closed by the plunger when it is depressed, a stop for limiting the downward stroke of the plunger, a discharge passage leading from the lower portion of the cylinder to a point adjacent the railhead, a one-way valve in the discharge passage, means for elevating the plunger, a head telescopically fitted to the plunger and positioned to be depressed by the wheel flange, and means for restraining movement of the head with respect to the plunger until the plunger has engaged the stop.
  4. In a wheel flange oiler comprising a reservoir for holding oil adapted to be positioned adjacent the rail, a cylinder block positioned in the reservoir, a plunger in the cylinder, a port in the cylinder wall for receiving oil from the reservoir, said port being closed by the plunger when it is depressed, a stop for limiting the downward stroke of the plunger, a discharge passage leading from the lower portion of the cylinder to a point adjacent the railhead, a one-way valve in the discharge passage, means for elevating the plunger, a head telescopically fitted to the plunger and positioned to be depressed by the wheel flange, and a spring interposed under partial compression between the head and plunger, said spring being of sufficient strength to resist movement of the head with respect to the plunger until the downward stroke of the plunger has been completed.
  5. In a wheel flange oiler comprising a reservoir for holding oil adapted to be positioned adjacent the rail, a cylinder block positioned in the reservoir, a plunger in the cylinder, a port in the cylinder wall for receiving oil from the reservoir, said port being closed by the plunger when it is depressed, a stop for limiting the downward stroke of the plunger, a discharge passage leading from the lower portion of the cylinder to a point adjacent the railhead, a one-way valve in the discharge passage, a head telescopically fitted to the plunger and positioned to be depressed by the wheel flange, interengaging members on the head and plunger for permitting limited vertical movement of the head with respect to the plunger, a spring interposed between the head and plunger, and a second spring interposed between the head and the cylinder block for elevating the plunger, said first mentioned spring being of sufficient strength to prevent movement of the head with respect to the plunger until the downward stroke of the plunger has been completed by engagement with the stop.
  6. In a wheel flange oiler comprising a reservoir for holding oil adapted to be posi-

tioned adjacent the rail, a cylinder block positioned in the reservoir, a plunger in the cylinder, a port in the cylinder wall for receiving oil from the reservoir, said port being closed by the plunger when it is depressed, a stop for limiting the downward stroke of the plunger, a discharge passage leading from the lower portion of the cylinder to a point adjacent the railhead, a one-way valve in the discharge passage, a head telescopically fitted to the plunger and positioned to be depressed by the wheel flange, interengaging members on the head and plunger for permitting limited vertical movement of the head with respect to the plunger, a spring interposed between the head and plunger, a stop on the head engaging a portion of the reservoir for limiting upward movement of the plunger and head, and a spring interposed between the cylinder block and head for elevating the plunger after it has been depressed, said first mentioned spring preventing relative movement of the head on the plunger until further downward movement of the plunger is prevented by engagement with the first mentioned stop.

7. In a wheel flange oiler comprising a reservoir for holding oil adapted to be positioned adjacent the rail, a pump including a cylinder, a port connecting the cylinder with the reservoir, a passage for discharging oil from the pump against the wheel flange, a stop for limiting the downward stroke of the plunger, a head telescopically fitted to the upper end of the plunger and adapted to be depressed varying distances by the engagement therewith of car wheel flanges of different diameters, a stop for limiting the upward movement of the head, means for preventing separation of the head and plunger, a spring for elevating the head and plunger, and a relatively strong spring confined between the head and plunger, the head and plunger normally moving as a unit throughout the stroke of the plunger, and any excess downward movement of the head being permitted by compression of the relatively strong spring.

PERRY H. HAMILTON.
